FIG. 4.

INVENTOR

Warren S. Herron,
Frank W. Thomas,
By John C. Crampton,
Witness.

UNITED STATES PATENT OFFICE.

WARREN S. HERRON, OF CENTERVILLE, MICHIGAN, AND FRANK W. THOMAS, OF TOLEDO, OHIO, ASSIGNORS TO DR. DENTON SLEEPING GARMENT MILLS, OF CENTERVILLE, MICHIGAN, A CORPORATION OF MICHIGAN.

GARMENT.

1,378,863.

Specification of Letters Patent. Patented May 24, 1921.

Application filed January 10, 1921. Serial No. 436,051.

To all whom it may concern:

Be it known that we, WARREN S. HERRON, and FRANK W. THOMAS, citizens of the United States, and residents of Centerville, St. Joseph county, Michigan, and Toledo, Lucas county, Ohio, respectively, have made an Invention Appertaining to Garments; and we do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to wearing apparel, and particularly to sleeping and other loose fitting garments of the type having drop-flap seats.

The object of the invention is to improve on the cut and form of garments of this class whereby the seat may have the desired fullness therein without the provision of the customary gussets in the crotch.

The invention is fully described in the following specification, and while in its broader aspect, it is capable of embodiment in different forms, a preferred embodiment thereof is illustrated in the accompanying drawings, in which,—

Figure 1 is a rear view of a sleeping garment embodying the invention. Fig. 2 is an enlarged central section thereof on the line 2—2 in Fig. 1. Fig. 3 is a fragmentary rear elevation of the garment with the drop-flap in open position, and Fig. 4 is a similar view of the garment as it appears before attaching the drop-flap thereto.

Referring to the drawings, 1 designates a sleeping garment, in the present instance, of the type made from cloth tubing and having the legs 2 thereof formed by cutting a V-shaped strip from the lower end of a tubing section and then sewing the open edges, as well understood in the art. In forming the legs in this manner, no gussets are customarily employed in the crotch to provide fullness in the seat.

In carrying out the present invention, the back of the garment is provided with a cross-slit 3 (Fig. 4) a short distance above the crotch and extending across the back. This slit is cut on a curve struck from a point be-

low the crotch so that the upper free edge of the seat flap 4 formed thereby is of convexed form. It is preferable that the base or fold line of the flap 4, which line is indicated by the dotted line 5, in Fig. 4, is extended cross-wise of the garment at a point slightly above the crotch.

The drop-flap 6 for the seat opening has its lower edge of convexed form to correspond to the convexity of the flap 4 and is sewed or attached at such edge to the edge of the flap 4 so that when the latter flap is turned down the drop-flap will extend upward therefrom in substantially flat form, as shown in Figs. 1 and 2. The upper free edge of the drop-flap is buttoned across the garment back above the slit 3 in a position which will allow the flap 4 to hang down, thereby providing considerable fullness in the seat. The drop-flap 6 may be broader than the length of the slit and in such case the lower side edge portions of the drop-flap, which extend beyond the ends of the slit 3, are sewed to the adjacent upper edge portions of the slit, as shown in Fig. 3.

It is evident that with our invention fullness may be provided in an easy and inexpensive manner in the seats of garments of the loose fitting type, such for instance, as sleeping garments, overalls, jumpers and the like, and obviates the use in the crotch of gussets for such purpose.

We wish it understood that our invention is not limited to any specific construction, form or arrangement of the parts, nor to its use in connection with a garment made from cloth tubing, as it is capable of numerous changes without departing from the spirit of the claims.

Having thus described our invention, what we claim as new, and desire to secure by Letters Patent, is,—

1. A garment having a seat-flap and a drop-flap with convexed edges secured to each other to provide fullness.

2. A garment having above its crotch a seat-flap with an upper convex edge, and a drop-flap provided with a lower convex edge attached to the convex edge of the seat-flap to provide fullness.

3. A garment of the class described, having an upwardly curved transverse slit across its back forming a seat-flap with an

upper convex edge, and a drop-flap having a lower convex edge attached to the convex edge of the seat-flap to provide fullness.

4. A garment of the class described, having an upwardly curved transverse slit across its back above the crotch and forming a seat-flap with an upper convex edge, such flap normally hanging downward, and a drop-flap having a lower convexed edge

attached to the convexed edge of the seat-flap and adapted to have its upper edge releasably attached to the garment back above the slit.

In testimony whereof, we have hereunto signed our names to this specification.

WARREN S. HERRON.
FRANK W. THOMAS.
